(57) **CLAIM**

The ornamental design for a display screen with graphical user interface as shown and described.

DESCRIPTION

The FIGURE is a front view of an image for a display screen with graphical user interface showing my new design. The peripheral dash-dot-dash lines illustrate a display screen or portion thereof and form no part of the claimed design. The broken lines depict portions of the display screen with graphical user interface that form no part of the claimed design. The grayscale shading represents a contrast in appearance of the display screen with graphical user interface and forms part of the claimed design.
